UNITED STATES PATENT OFFICE.

ARNOLD RUTISHAUSER, OF OLLEN, SWITZERLAND, ASSIGNEE TO FIRM MOTOR-WAGENFABRIK EBENNA A-G., OF OLLEN, SWITZERLAND.

ROTARY DIGGING-MACHINE.

1,383,761.

Specification of Letters Patent. Patented July 5, 1921.

Application filed April 8, 1920. Serial No. 372,181.

To all whom it may concern:

Be it known that I, ARNOLD RUTISHAUSER, a citizen of the Republic of Switzerland, residing at Olten, Felsenstrasse 853, Switzerland, have invented certain new and useful Improvements in Rotary Digging-Machines; and I do hereby declare the following to be a clear, full, and exact description of the invention, such as will enable others skilled in the art to which it appertains to make and use the same, reference being had to the accompanying drawing, and to letters or figures of reference marked thereon, which form a part of this specification.

15 The invention relates to improvements in rotary digging machines, the hoes of which are resiliently connected to a drum, by which connection the hoes are adapted to yield to some extent when entering the soil.

20 The arms of the hoes are fixed to a common drum.

The hitherto known constructions of such machines present many drawbacks. These machines are provided with a drum carrying the hoes, which rotates in the same direction as the wheels on which the machine runs, the hoes being adapted to swing around an axis parallel to the axis of the drum or around the axis of the drum itself. 25 A stop is provided for each hoe to limit the swinging movement of the arms of the hoes. A spring is arranged between each arm of the hoes and the stops. These springs are left wholly unprotected and soil and small stones lodge around them thus rendering them quite useless. Furthermore the stops limit the working depth of the hoes inasmuch as only that part projecting beyond the stops can penetrate into the earth.

30 The object of the present invention is to remedy the above-mentioned disadvantages by arranging the springs in such a manner that they are protected from the soil, further by omitting stops for the hoes and by 35 avoiding the gathering of roots and fibers at the hoes in arranging them back of a curved edge, which arrangement increases the action of the hoes on the soil.

In the construction of the present invention the arms of the hoes are secured between a pair of plates adapted to swing around the axis of the drum. A second pair of plates is provided fixed to the axle and rotating with the axle of the drum, circular 45 springs being inserted between the two

pairs of plates, which cause a resilient transmission of the rotary motion of the fixed plates to the swinging plates which carry the hoes.

Preferably the arms of the hoes are so constructed that the part inserted between the swinging plates is provided with a hole to take up a bolt, and that the end of the arm rests against a ring provided on the driving axle and against a pin secured to the fixed plates. At their working end the edge of the flat arms of the hoes toward the front of the machine is of a convex shape and the arms are provided with a hoe that stands back of that curved edge. This curved edge and the relative position of the hoe against this edge have the effect that roots which would likely deposit themselves on the part where the hoe is connected to the arm are guided toward the periphery of the drum and thrown off.

The accompanying drawing shows by way of example one mode of carrying out the invention. In this drawing:

Figure 1 is a side view, parts of the plates being broken away to show the inner end of the arms and springs;

Fig. 2 is a section along line II—II of Fig. 1;

Fig. 3 is a section along line III—III of Fig. 1.

A driving axle 1 of hexagonal section carries a ring 2 the bore of which is of a corresponding hexagonal shape and fits on axle 1. At each side of ring 2 a plate 3 is fitted to the hexagonal axle, thus the plates 3 rotate with the driving axle. Between the plates 3 a pair of plates 4 is inserted; and the arms 5 of three hoes being fixed between the last mentioned plates 4. Bolts 6 and pins 13 serve to hold the arms 5 in position between the plates. Circular openings 7 are provided in the outer plates 3 and in the inner plates 4 to receive circular laminated springs 8. These circular springs are protected from coming out of the openings 7 and from getting into contact with earth by covers 9 connected to each other by a bolt 10. The turning of the circular springs into an inoperative position is prevented by a bar 11, held in position at one end by the bolt 10 and at the other end by a pin 12 arranged in the plates 4. These springs revolved by the outer plates 3 transmit the rotary movement to the inner plates 4 and 130

therefore to the hoes connected to the latter. At the ends 14 resting against the ring 2, the arms 5 of the hoes inclose partially the pins 13 secured to the inner plates 4. The end 5 14 of the arm of a hoe projects between pin 13 and ring 2 and is of such a shape that after unscrewing bolt 6 the arm of the hoe can easily be removed when a small turning motion of the arm around pin 13 is executed.

10 The working edge of each flat arm 5 is of convex curvature and is fitted at the end projecting beyond the inner plates 4 with a hoe 17 beveled at its sides and standing back in relation with the curved edge.

15 Preferably the driving axle 1 is provided with a plurality of spider-like units formed by the hoes and arranged on the axle, each unit consisting of three hoes connected to 20 the plates in the manner shown in Figs. 1, 2 and 3. Advantageously the arms of the adjacent units are turned against each other. The separate units are threaded on the driving axle spaced by bushings 15 and then 25 pressed together by nuts 16, the ring 2 having such a thickness that sufficient clearance is provided to allow an unrestricted movement of the inner plates 4 inside the outer plates 3. The ring 2 serves at the same time 30 to center the inner plates 4.

35 A great advantage of the digging apparatus shown consists in the fact that all three circular springs 8 take part simultaneously in producing the momentary resiliency of any single working hoe. This circumstance allows of using single circular springs of comparatively small dimensions and of placing them near the driving axle 1. The great advantage results thereof that the 40 lengths of the arms of the hoes used for active work are considerably increased. The fastening of the hoes gives a good ratio between the length of the fixed part and the free part of the hoe arms on which their 45 lateral elasticity depends. An increased lateral elasticity of the hoes is of great importance when stones or other objects causing a considerable resistance are struck by the hoes.

50 I claim:

1. In a rotary digging unit, the combination of a driving axle, a pair of plates spaced apart and fixed on said axle, a second pair of plates centered on said axle arranged between and connected to the first pair by a resilient connection and a plurality of hoes the arms of which are arranged between the second pair of plates.

2. In a rotary digging unit, the combination of a driving axle of profiled section, a pair of plates spaced apart and fixed on said axle, a spacing ring fixed to the axle, a second pair of plates centered on said ring between the first pair of plates and a resilient connection between the pairs of plates and

hoes, the flat arms of which are arranged between the second pair of plates.

3. In a rotary digging unit, the combination of a driving axle, a pair of plates spaced apart and fixed on said axle, a second pair of plates centered on said axle and arranged between the first pair of plates, a resilient connection between the pairs of plates, a ring on said axle, and hoes having arms which are arranged between said second pair of plates and detachably connected thereto, the inner end of said arms resting against said ring, and a pin secured to the first pair of plates against which said arms bear.

4. In a rotary digging unit, the combination of a driving axle, a pair of plates spaced apart and fixed on said axle, a second pair of plates centered on said axle arranged between the first pair of plates, a resilient connection between the pairs of plates, and hoes having arms which are arranged between said second pair of plates and detachably connected thereto, the working edge of said arms being convex.

5. In a rotary digging machine, the combination of a driving axle, a pair of plates, spaced apart and fixed on said axle, a second pair of plates centered on and loose on said axle, arranged between the first pair of plates, a resilient connection between the pairs of plates, and hoes having arms which are arranged between said second pair of plates and detachably connected thereto, the working edge of the arms being convex and arranged in advance of the hoes.

6. In a rotary digging unit, the combination of a driving axle, a pair of plates spaced apart and fixed to said axle, a second pair of plates centered and loose on said axle arranged between said first pair of plates, circular holes provided in both pairs of plates, circular springs inserted in said holes and acting as resilient connections between the two pairs of plates, and hoes having arms which are arranged between the second pair of plates and detachably connected thereto.

7. In a rotary digging machine, the combination of a driving axle, a pair of plates spaced apart and fixed to said axle, a second pair of plates loose on said axle arranged between the first pair of plates, a resilient connection between said pairs of plates, hoes having flat arms which are arranged between said second pair of plates and detachably connected thereto, the afore-mentioned parts forming a digging unit on the axle, a plurality of such units arranged on the axle, and spacing bushings between said units.

8. In a rotary digging machine, the combination of a driving axle, a pair of plates spaced apart and fixed to said axle, a second pair of plates loose on said axle arranged between the first pair of plates, a resilient connection between the pairs of plates, hoes

having flat arms which are arranged between said second pair of plates and detachably connected thereto, and a ring for spacing the plates of the first pair from one another to an extent sufficient to provide the necessary clearance for a swinging movement of the second pair of plates between and relatively to the first pair.

9. In a rotary digging unit, a shaft, a pair

of plates rigidly secured thereto, a second pair of plates between the plates of the first pair and loose with respect to said shaft, digging arms secured between the plates of the latter pair and circular springs extending through both pairs of plates.

In testimony that I claim the foregoing as my invention, I have signed my name.

ARNOLD RUTISHAUSER.
